UNITED STATES PATENT OFFICE.

CHARLES J. HUBER, OF BALTIMORE, MARYLAND, ASSIGNOR TO HUBER GRATE BAR & STOKING COMPANY, OF BALTIMORE, MARYLAND, A CORPORATION OF DELAWARE.

FURNACE-GRAVE.

1,232,687.

Specification of Letters Patent. Patented July 10, 1917.

Application filed February 1, 1916. Serial No. 75,503.

To all whom it may concern:

Be it known that I, CHARLES J. HUBER, a citizen of the United States, residing at Baltimore, in the city of Baltimore and State 5 of Maryland, have invented new and useful Improvements in Furnace-Grates, of which the following is a specification.

This invention relates to furnace grates, the object in view being to produce a grate 10 of high efficiency by means of which the fuel may be fed along the grate surface while being consumed, at any rate of progress desired by the attendant so that a uniform distribution of the fuel is insured. 15 The construction and operation of the grate is such that the fire may be increased or allowed to diminish in accordance with the heat required. Furthermore, the construction and arrangement is such that the oscillatory grate sections hereinafter more particularly described only protrude into the fire or bed of coals momentarily thereby keeping the grate in a comparatively cool condition and avoiding to a considerable 20 extent the tendency of the grate sections to warp and bind in their bearings. A further object of the invention is to provide in connection with an inclined series of oscillatory grate sections, manually controlled 25 levers and connections whereby groups of alternately arranged sections may be actuated, combined with means for arresting the movement of each manually controlled lever independently of the other and sus- 30 taining the fuel supporting surfaces of the grate sections in a common plane. Greater or less movement may be imparted to the grate sections as desired and they may be operated quickly or slowly in accordance 35 with the necessity of advancing the fuel rapidly or slowly.

With the above and other objects in view, the invention consists in the novel construction, combination and arrangement of parts, 40 as herein described, illustrated and claimed.

In the accompanying drawings:

Figure 1 is a vertical section through a furnace, showing the grate of this invention partly in side elevation and partly in section. 50

Fig. 2 is a similar view showing one group of grate sections tilted for advancing the coked fuel.

Fig. 3 is a similar view showing the dumping grate section lowered. 55

Fig. 4 is an enlarged detail side elevation of one of the supporting bars.

Fig. 5 is a fragmentary vertical cross section on the line 5—5 of Fig. 1, on an enlarged scale. 60

Fig. 6 is an enlarged plan view of one of the grate sections.

Fig. 7 is a rear elevation of the same.

Fig. 8 is an end elevation of one of the 65 grate sections.

Fig. 9 is a vertical cross section on the line 9—9 of Fig. 6.

Fig. 10 is an end view of one grate section showing a fragment of the next grate 70 section adjacent the lip, in co-operative relation thereto.

Great difficulty has been experienced in producing a grate of such a construction as to insure the uniform feeding of the fuel along the grate surface at a proper rate of progress, and also to enable the rapidity of feed of the fuel to be increased or diminished as required in accordance with conditions existing at any particular time. The 75 grate hereinafter particularly described and illustrated in the drawings has been especially designed to overcome the objections referred to and which up to this time have been fatal to the practical efficiency of 80 grates of the general type embodied in this application. 85

In carrying out the present invention, I employ any suitable number of supporting bars one of which is illustrated in side elevation in Fig. 4. Each supporting bar comprises a substantially vertical web-like body 1 of truss formation, said bar being provided at one end thereof with an attaching lug 2 and provided at the opposite end thereof with a supporting lug 3. In its upper margin the supporting bar is provided with a longitudinal series of journal receiving sockets 4 and 5 and it will be observed that each of said sockets comprises a wall 6 which is substantially straight and is inclined or oblique with respect to the length of the bar, the oblique walls of the sockets 6 inclining toward the front of the furnace and the oblique walls 6 of the socket 5 inclining in the opposite direction or toward the rear wall of the furnace, the front wall of the

furnace being indicated at 7 and the rear wall at 8.

Each of the supporting bars 1, as shown in Fig. 5, is provided at one side thereof with a laterally projecting flange 9 which extends under the journals of the grate sections hereinafter described and as shown in Fig. 5 and overhangs the connecting rods by which the grate sections are oscillated. Where grate sections are arranged at both sides of a supporting bar 1, the latter is provided with two of such flanges 9 as shown in Fig. 5 and these flanges, whether one or two are employed, follow the outline of the upper marginal edge of the body of the supporting bar including the journal receiving sockets 4 and 5.

The fuel supporting surface of the grate is made up of an inclined series of oscillatory grate sections 10, said series sloping downwardly at a certain predetermined angle from the front toward the rear of the furnace as clearly indicated in Figs. 1, 2 and 3. Each of the grate sections is constructed as best illustrated in Figs. 6 to 9 inclusive, the same comprising a series of parallel grate bars 11 which are connected intermediate their front and rear extremities by means of a stringer bar 11' and are further connected at their front extremities by means of a guard wall 12. Each of the grate bars 11 is of the shape best illustrated in Fig. 9, the bars 11 being of greater depth or vertical extent at the front than at the rear of the grate section. The grate section is provided at its opposite extremities with projecting journals 13 and is also provided with bearing shoulders or bosses 14 to prevent the operating arms hereinafter described from rubbing against the supporting bars 1 thus reducing friction to a minimum and enabling the grate sections to be oscillated with comparative ease. At their forward extremities the grate bars 11 are rounded as shown at 140 so as to lie flush with the journals 13. Each grate bar 11 thus comprises a curvilinear portion 140 and a rectilinear portion 145. This produces a clinker crushing projection at the rear extremity of the bar 11, the series of clinker crushing projections thus provided on each grate section serving to break up the cinders during the oscillatory movements of the grate sections thus eliminating large clinkers forming under the bed of coals.

The guard wall 12 gradually decreases in thickness from top to bottom as shown in Fig. 9 and the outer surface 16 thereof together with the adjacent edges 17 of the grate bars 11 are described on an arc of a circle of which the axis of the journals 13 is the center. Each grate section is also provided at one end only thereof with an operating arm 18 and a portion of the forward edge of said arm is also described on the

foresaid arc as shown at 19. The object in describing the parts referred to on the arc above mentioned is to render it possible to rock each grate bar section into the position indicated in Fig. 2 where the fuel supporting top surfaces of certain grate sections are shown as approaching a vertical line. The shape and angular disposition of the operating arm 18 of each grate section 10 are such that if necessary the fuel supporting top surface of said grate section may be carried beyond a vertical line, this being rendered possible by extending the arm 18 obliquely downward with respect to its grate section and terminating said arm at a point in rear of the body of the grate section and at a point in rear of an imaginary vertical line passing through the body of the next adjacent grate section. This last named feature is clearly illustrated in Figs. 1, 2 and 3 and also in the detail sectional view, Fig. 9.

The guard wall 12 has its upper or top portion expanded in width or thickness to form a projecting ledge 20 which as shown in Fig. 10 overhangs the adjacent portion of the next grate bar 10, the object of this being to prevent coal from sifting downwardly between the grate sections which would be productive of considerable waste of fuel. The upper marginal portion of the guard wall 12 is concaved as at 21 on an arc of a circle of which the axis of the journals 13 is the center. Therefore the clearance space between adjacent grate sections is unvarying and is sufficiently small to prevent waste of coal. This is due especially to the overhanging arrangement of the projecting ledge 20. It will also be noted that the guard wall 12 does not extend downwardly to the full depth of the rear portions of the grate bars 11 and therefore when the grate section is rocked upwardly to the position shown in Fig. 2, free draft will be allowed between the grate bars 11 and thus the draft is not interfered with by said guard wall. The stringer bar 11' and the grate bars 11 as well as the guard wall 12 gradually decrease in thickness from top to bottom thereby causing them to easily clear themselves from adhering accumulations and also making the grate section as a whole easier to draw from the sand of a mold. At its extremity, each operating arm 18 is preferably provided with an annular bearing boss 22 which comes in contact with the adjacent connecting rod 23 and thereby prevents the body of the arm 18 from rubbing against said connecting rod and producing unnecessary friction.

As many series of oscillatory grate sections A may be employed as required by the width of the furnace and in connection with each series of such grate sections, I employ a pair of connecting rods 23 as clearly indicated in Fig. 5, the said connecting rods lying beneath and being pro-

tected by the overhanging flanges 9 of the intervening supporting bar 1, which prevents the siftings from the grate from falling upon the connecting rods or bars 23 and 5 the pivotal connections between said bars and the operating arms 18 of the adjacent grate sections. Each arm 18 is shown as connected to one of the rods or bars 23 by means of a pivot 24 which is inserted through 10 a smooth hole in the arm 18 and threaded into an opening in the respective connecting rod 23 where it is fixedly held by means of a set screw 25 screwed into the rod 23 and binding against the threaded portion of the 15 pivot 24. This prevents any possibility of the pivot 24 working loose and permitting the arm 18 to become disconnected from the rod 23. It will be noted by reference to Figs. 1, 2 and 3 that one of the connecting 20 rods 23 is pivotally associated with one group of oscillatory grate sections, said group being composed of every other grate bar section. The other connecting rod 23 is similarly associated with the remaining 25 grate bar sections.

Each of the connecting rods 23 is actuated independently of the other by means of a manually operated lever designated generally at B and comprising a base section 26 and a detachable section 27. The base or main section 26 is operatively connected with the respective connecting rod 23 by means of a telescopic coupling rod designated generally at C and comprising a 30 tubular member 28 and a rod-like member 29 which is slidable in the member 28 and held at any desired adjustment by means of a binding screw 30 carried by the member 28. The coupling rod C is pivotally connected at 31 to the respective connecting rod 23 and is pivotally connected at 32 to the base section 26 of the lever B, said base section being shown as fulcrumed at 33 on an arm or bracket 34 fastened to the front wall 45 of the furnace.

The section 26 of the lever B is formed with a socket at 35 to receive the section 27 of the lever which may be readily detached from the section 26 when not in use and the 50 section 26 is provided with a laterally extending stop 36 which is adapted to come in contact with the front wall 7 of the furnace when the fuel supporting surfaces of the grate sections are in a common plane. The 55 lever section 27 is also preferably constructed in such manner as to provide a stop surface 37 which also comes in contact with the front wall of the furnace and performs the same function as the stop 36.

60 38 designates the dead plate or coking plate at the front end of the inclined grate and just within the fuel door opening 39. 40 designates the dumping grate section the journals 41 of which are received in the 65 sockets 5 of the supporting bar or bars. An

operating connection 42 is pivotally attached to the dumping grate section 40 at 43 and extends through the front wall of the furnace where it is provided with a suitable operating handle 44.

70 From the foregoing description, taken in connection with the accompanying drawings, it will now be understood that the oscillatory grate sections are arranged in a rearwardly sloping series and the journals thereof being mounted in the sockets 4 and 5, even should one or more of the grate sections become warped or overheated, the shape of the sockets 4 and 5 will permit the journals of the grate sections to shift themselves in order to compensate for such warping of the grate sections without liability of any binding action, thus maintaining the grate sections in perfect working condition and relation to the supporting means therefor. The pivotal connection between the grate sections and the connecting rods 23 is protected by the overhanging flanges 9 of the supporting bars 1 thereby preventing siftings from finding their way to the pivotal connections referred to and also assisting in keeping the working parts of the grate in good condition. On account of the grate sections being alternately connected to an operating lever, every other grate section may be rocked upwardly for feeding the fuel toward the rear end of the grate and a slow movement may be imparted to the said grate sections by a corresponding movement of the lever by which said sections are operated. 100 The grate sections are in the fire or bed of coals only for a moment or during the operation of the respective lever B thereby attaining a distinct advantage over any eccentric-operating means which has the serious defect of keeping portions of the grate sections for too long a period in the bed of coals and thereby increasing the liability of warpage of the parts. The fuel supporting surfaces of the grate sections are maintained in a common plane by means of their actuating levers and the stops above described. By reason of the special formation and arrangement of the operating arms 18 of the 105 grate sections, the fuel supporting surfaces of said sections may be carried upwardly to and even beyond a vertical line so as to positively insure the progressive movement of the fuel while at the same time breaking up any crust or sheet-like clinkers which may 110 form above the grate.

Having thus described my invention, I claim:

1. In a furnace grate, the combination with supporting means, of a rearwardly sloping series of oscillatory grate sections each embodying a plurality of grate bars, a stringer bar intersecting said grate bars between the front and rear extremities thereof, and a guard wall also intersecting said 125

- grate bars at the extremities thereof, the lower portion of the outer face of said guard wall and the adjacent extremities of the grate bars being described on the arc of 5 a circle of which the axis of movement of the grate section is the center, the upper portion of the outer face of the guard wall being concave on an arc of which the axis of the adjacent bar is the center.
- 10 2. In a furnace grate, the combination with supporting means, of a rearwardly sloping series of oscillatory grate sections each embodying a plurality of grate bars, a stringer bar intersecting said grate bars between the front and rear extremities thereof, and a guard wall also intersecting said grate bars at the extremities thereof, the outer face of said guard wall and the adjacent extremities of the grate bars being described 15 on the arc of a circle of which the axis of movement of the grate section is the center, the upper marginal portion of the guard wall being offset on its outer side to form a projecting ledge which overhangs the adjacent portion of the next grate section.
3. In a furnace grate, the combination with supporting means, of a rearwardly sloping series of oscillatory grate sections each embodying a plurality of grate bars, a stringer bar intersecting said grate bars between the front and rear extremities thereof, and a guard wall also intersecting said grate bars at the extremities thereof, the outer face of said guard wall and the adjacent extremities of the grate bars being described 20 on the arc of a circle of which the axis of movement of the grate section is the center, the upper marginal portion of the guard wall being offset on its outer side to form a projecting ledge which overhangs the adjacent portion of the next grate section.
4. In a furnace grate, the combination with a rearwardly sloping series of oscillatory grate sections having end journals, of a supporting bar therefor embodying a substantially vertical web-like body formed with bearing sockets for said journals, said sockets being open at the top and each partly defined by a wall which is oblique with respect to the length of the supporting bar, one of said sockets having its oblique wall inclined in the opposite direction, and a dumping grate section having an end journal supported in the last named socket.
5. In a grate, the combination of a plurality of oscillatory grate sections arranged in abutting relation and in an inclined series, each section comprising parallel grate bars having rounded extremities, a stringer bar intersecting said bars adjacent to the rounded extremities thereof and having a substantially flat side forming clinker crushing faces between the rounded extremities of said bars, a guard wall extending downwardly from the opposite extremities of 65 said bars and described on an arc of which the axis of said section is the center, and means connecting said sections in two separate sets, each comprising alternate sections and manually controlled means for oscillating the sections of each set independently of the other set.
6. In a grate, the combination of a plurality of oscillatory grate sections arranged in abutting relation and in a series inclined 70 downwardly and rearwardly, each section comprising a plurality of bars the cross-sections of the bars increasing in vertical width from the rear toward the front, the axis of each section being adjacent the rear ends of 75 the bars of that section so that in oscillating the sections swing upward and backward toward the rear of the furnace, a guard wall extending downwardly over the forward extremities of the said bars for the 80 greater portion of the width of the bars and having the outside surface in the main described on a substantially circular arc of which the axis of said section is the center, each section having a lever arm, and separate means connected to the alternate lever arms forming two separate sets, and manually operated means co-operating with said means to oscillate the sections of each set independently of the other set.
7. A grate section for stoking grates consisting of a plurality of grate bars, a pivot at each end of the section transverse to the bars, the pivots being in alinement with each other and with the rear ends of the 90 bars, means connecting the ends of the bars in alinement with the pivots, each bar being of a width measured in a plane at right angles to the pivots increasing from the pivot toward the swinging ends of the grate 95 bars, a guard wall connecting the ends of the grate bars remote from the pivots and extending downward for a considerable portion of the width of the said ends of the bars an almost equal portion of the ends 100 of the grate bars being uncovered, substantially the entire outer surface of the guard wall and the surfaces of the adjacent ends of the grate bars being formed on a circular arc concentric with the pivots, and a lever 105 arm at right angles to the pivot.
- In testimony whereof I affix my signature in presence of two witnesses.
